United States Patent Office

Des. 182,910

Patented May 27, 1958

182,910

TABLE

John J. Lubberts and Lambert J. Mulder, Grand Rapids, Mich., assignors to Tomlinson of High Point, High Point, N. C., a corporation of North Carolina

Application March 27, 1957, Serial No. 45,453

Term of patent 14 years

(Cl. D33—14)

FIG. 1

We claim:

The ornamental design for a table, substantially as shown.
